UNITED STATES PATENT OFFICE.

SAMUEL P. THOMSON AND HOWELL C. ROCKHILL, OF FORT WAYNE, INDIANA.

CORRUGATING MACHINERY.

Application filed February 7, 1927. Serial No. 166,456.

This invention relates to improvements in corrugating machinery especially applicable to iron bars employed in the reinforcement of concrete roads and other structures. The object of the improvement is to provide a machine of high capacity for corrugating iron bars that will be continuous and self feeding in operation. Another object is to so construct the machine as to permit of adjustment whereby the angularity of the corrugations formed in the iron-bar may be varied more or less accordingly as adjustments are made, and another object is to provide the corrugating members with replaceable parts at those portions thereof that are subjected to the severest stress and wear.

These objects are accomplished by the construction illustrated in the accompanying drawings, in which:—

20 Fig. 1 is a plan view of a machine embodying the invention, there being included a bar in course of progression through the machine;

Fig. 2 is an elevation projected from Fig. 1, portions thereof being omitted; and

25 Fig. 3 is a detail plan view of the adjusting means as applied to one of the corrugating members.

The characters appearing in the description refer to parts shown in the drawings and designated thereon by corresponding characters.

30 The invention is constituted of a bench 1 having a flat top 2 supported on legs 3 and having transversely disposed channel beams 4 and 5, said beams being disposed in parallel relation with each other, one above the other.

35 The legs 3 on each side of the bench are connected by corresponding horizontal beams 6 that support a pair of bearings 7 and 8 respectively.

40 In supported relation with the beams 4 and 5 are disposed a pair of spaced bearings 9 and 10 respectively, each of which extends upwardly through the top 2 of the bench, and has mounted therein a corresponding vertical shaft 11—12 provided at its lower end with a miter gear 13—14.

45 In the bearings 7 is journaled a countershaft 15 having fixed thereon a pair of miter gears 16—17 that have engagement respectively with the former miter gears on said vertical shafts, and being so disposed as to actuate said former miter gears in opposite directions when said countershaft is rotated. Upon the outer end of the countershaft is fixed a gear 18 that has actuated relation with a pinion 19,

which pinion is fixed on a drive-shaft 20 journaled in the bearings 8. The drive-shaft is provided with a fixed drive-wheel 21 to which is applied a belt (not shown) by which it is actuated. The bearing 10 has a foot 22 at its lower end and also at a point spaced from its upper end, said feet being provided with slots 23 through which bolts 24 extend for securing said feet to the corresponding beams 4 and 5. The slots are so disposed as to admit of adjustable movement lengthwise in the corresponding beams, there being provided an adjusting screw 25 in the upper part of the bench at one side thereof that bears against the corresponding foot 22 and acts 60 to prevent spreading movement of the bearing 10 relative to the bearing 9.

Upon the upper end of each vertical shaft 11—12 is fixed a corresponding rotor 26—27, the one being the counterpart of the other and 75 having the form of a star. Each rotor has an annular series of male dies 28 that form respectively the points of the star, and also an annular series of female dies 29 that form the respective crotches of the star. A series of radial ribs 30 on each rotor abut the respective dies 28—29 whereby said dies are sustained. The rotors are so positioned on their respective shafts that the male dies of each rotor articulate with the corresponding female dies of 80 the other rotor.

At the front and back of the bench is provided a corresponding pair of guide members 31—32 for the purpose hereinafter stated.

The dies are made of hardened metal and 90 are removably applied in their respective positions on the corresponding rotor by any suitable means, such as is ordinarily resorted to, by which they are held rigidly in place.

In the operation of the invention an initially straight bar of iron 33 is introduced onto the top of the bench by passing it endwise between the guides 31, and the rotors are set in motion by the action of the driving mechanism. The bar is then manually progressed forwardly upon the top of the bench and between the rotors to such extent as to become caught between one of the male dies of one rotor and the corresponding female die of the other, whereupon the bar is drawn, by the action of the rotors therebetween, and progressed over the bench and between the guides 32 in a corrugated state, there being formed in the bar a succession of spaced bends 34 of alternate and opposite angularity. The 100 105 110

guides 31 and 32 confine flatwise swaying movement of the bars of iron as they are passed through the machine.

By adjustment of the bearing 10 in the cross beams the rotor 27 is adjustably spaced from the rotor 26, and thereby the angularity of the bends made in the bar in its passage between the rotors are made more or less severe accordingly.

10. What we claim is:—

1. A machine for corrugating iron bars including a bench; a pair of transverse beams in the bench structure; a pair of spaced bearings, one of which is adjustably movable so as to vary the space between said bearings; a vertical shaft in each of said bearings; a driving gear mechanism having actuating relation with said vertical shafts operable to rotate the shafts in opposite directions; a rotor 20 fixed on the upper end of each shaft in a plane above the top of the bench, the one rotor being the counterpart of the other, and each having the form of a star; an annular series of removable male dies on each rotor located 25 thereon to form the star points thereof respectively; an annular series of removable female dies on each rotor located thereon forming the crotches thereof respectively, said rotors being so disposed that the star points of each rotor articulate correspondingly with the crotches of the other rotor as said rotors are revolved; and spaced guide members at each end of the bench operable to limit lateral swaying movement of said bars.

30. 2. A machine for corrugating iron bars including a bench structure; a pair of spaced bearings including means for adjustably spacing said bearings; a vertically disposed shaft in each of said bearings; a mechanism having actuating relation with said vertical shafts operable to rotate said shafts in opposite directions; a star shaped rotor fixed on the upper end of each shaft in a common plane with each other above the top of the bench, one rotor being the counterpart of the other, said rotors being so disposed that the

points of each rotor articulate correspondingly with the crotches of the other rotor as said rotors revolve; and spaced guide members operable to limit lateral swaying movement of said bars.

3. A machine for corrugating iron bars including a bench structure; a pair of spaced bearings including means for adjustably spacing said bearings; a vertically disposed 55 shaft in each of said bearings; a mechanism having actuating relation with said vertical shafts operable to rotate said shafts in opposite directions; and a star shaped rotor fixed on the upper end of each shaft in a common 60 plane with each other above the top of the bench, one rotor being the counterpart of the other, said rotors being so disposed that the points of each rotor articulate correspondingly with the crotches of the other rotor as said 65 rotors revolve.

4. A machine for corrugating iron bars comprising two or more companion substantially star-shaped rotors, arranged in intermeshing pairs, renewable die members at the 70 points and crotches respectively of said rotors, means for simultaneously rotating said pairs of rotors in unison and in opposite directions, and means for limiting the lateral swaying movement of said bars.

75. 5. A machine for corrugating iron bars comprising two or more pairs of intermeshing substantially star-shaped rotors, shafts supporting said rotors, means for adjusting said pairs of rotors towards or from each other, means for simultaneously rotating the pairs of rotors and in opposite directions to each other, a plurality of removable male and female dies at the points and crotches respectively of said rotors, and means for limiting 80 the lateral swaying movement of said bars while being corrugated.

In testimony whereof we affix our signatures.

SAMUEL P. THOMSON.
HOWELL C. ROCKHILL.
